UNITED STATES PATENT OFFICE.

MAX C. WEBER, OF CLEVELAND, OHIO.

ELASTIC-FLUID TURBINE.

1,188,516.

Specification of Letters Patent. Patented June 27, 1916.

Application filed June 2, 1913. Serial No. 771,154.

To all whom it may concern:

Be it known that I, MAX C. WEBER, a citizen of the United States, resident of Cleveland, county of Cuyahoga, and State of Ohio, have invented a new and useful Improvement in Elastic-Fluid Turbines, of which the following is a specification, the principle of the invention being herein explained and the best mode in which I have contemplated applying that principle, so as to distinguish it from other inventions.

My invention relates to an elastic fluid turbine, and more particularly to detailed improvements in connection therewith.

The object is the provision of a turbine which, while economical of manufacture and simple of operation, will prove generally efficient.

The said invention consists of means which are hereinafter fully described and particularly set forth in the claims.

The annexed drawings and the following description set forth in detail certain mechanism embodying my invention, the disclosed means, however, constituting but one of various mechanical forms in which the principle of the invention may be disclosed.

In said annexed drawings:—Figure 1 is a front elevation of a turbine embodying my invention. Fig. 2 is a rear elevation of the turbine, partly in section. Fig. 3 is a side elevation, with other parts in section. Fig. 4 is a top plan of Fig. 1. Fig. 5 is a plan of one detail. Fig. 6 is a section on line VI—VI of Fig. 5. Fig. 7 is a plan of another detail.

Frame.—The construction of my turbine comprises a supporting frame A provided on one side with a standard a', and on the other with a hollow annular casing a². The standard a' is formed with three bearings a³, a⁴, a⁵, at different heights with respect to each other, and the purpose of which will presently more clearly appear. The annular casing a² is provided below with an opening a⁶ in integral registration with an opening in the base of the frame. The annular casing is furthermore provided with an opening a⁷ near the top thereof, in direct communication with an explosion chamber a⁸, also mounted as an integral construction above the same. The explosion chamber a⁸ is inclosed within the usual water jacket a⁹ provided with an inlet a¹⁰ and outlet a¹¹. Any suitable type of igniter a¹² is also seated in the chamber, as shown. Adjacent

the explosion chamber, and in direct horizontal communication therewith, as indicated by the arrow in Fig. 2, is a supply-chamber a¹³. Beyond the other end of the explosion chamber and adapted to come into communication therewith in a manner yet to be described is an expansion chamber a¹⁴. The annular portion a² of the frame is further shaped to form an auxiliary chamber a¹⁵ communicating with the interior of the casing through two openings, a¹⁶ and a¹⁷. This chamber is located intermediately of the expansion chamber a¹⁴ and the exhaust outlet opening a⁶, and is formed with the partition member a¹⁸ adapted to form in said chamber an angular passage having its inlet and outlet openings a¹⁶ and a¹⁷ respectively spaced some distance apart, as most clearly shown in Fig. 3. Mounted above the explosion and supply chambers a⁸ and a¹³ are two additional brackets a¹⁹ and a²⁰ respectively, provided with bearings a²¹ and a²², which are in direct line with the upper bearing a⁵ on the standard a'. The supply chamber a¹³ is also provided with a lateral bearing a²³ located in the same horizontal line with the bearing a⁴. An angular bracket a²⁴ has one arm fixedly secured to the standard a' immediately beneath the bearing a⁵, best seen in Fig. 2, and has its other arm provided with a bearing a²⁵ in line with each of the bearings a⁵, a²¹ and a²². Mounted above the supply and explosion chambers, and as shown, midway of the perpendicular planes thereof, is an upwardly extending bracket a²⁶ having right and left arms a²⁷ and a²⁸. These arms are formed with suitable bearings respectively a²⁹ and a³⁰. A plate a³¹ is positioned in front of the machine, between the bearings a⁸ and a⁴, and supported upon a suitable bracket a³². The upper inclined surface of the plate a³¹ is provided with a plurality of notches a³³, best seen in Fig. 1. The function of these notches will be presently manifested.

Rotor.—A primary rotor shaft B is horizontally mounted in the bearing a², and two additional bearings a³⁴ and a³⁵, positioned on opposite axial sides of the hollow annular casing a², as clearly seen in Fig. 1. A splined shaft C is horizontally mounted in the bearings a⁴ and a²³. A crank-shaft D is horizontally mounted in the bearings a⁵, a²⁴, a²¹ and a²². The conjunctive purpose of the shafts C and D will be more fully explained in later paragraphs. Mounted upon

the shaft B within the hollow annular casting a^2 , so as to present a close mechanical fit therewith, is a rotor b' . This is preferably fixed about a hexagonal portion b^2 of the primary shaft B. The rotor b' is provided with the usual type of peripheral vanes b^3 forming the intermediary comparatively shallow buckets, alternate of which I will designate as b^4 and b^5 , for the purpose of a better understanding of certain features of my invention. As mounted within the hollow annular casing a^2 , the buckets are necessarily adapted to communicate successively with the chamber a^{14} , the auxiliary chamber a^{15} and the exhaust outlet a^6 , as clearly apparent from an inspection of Fig. 3, and indicated by the arrow designating the proposed direction of movement. The arrangement of the openings a^{16} and a^{17} is such that they may simultaneously communicate with alternate buckets. In Fig. 3, these are shown to be b^4 and b^5 . At the moment of the beginning of such intersection, the intermediary bucket b^5 is entirely shut off from communication with the auxiliary chamber a^{15} . It will be noted, therefore, that the gases in the rear of the buckets b^4 being still under sufficient compression to expend a very high degree of energy in the form of velocity, will immediately upon registration of these buckets with the opening a^{16} , rush through the latter and expend their residual energy in the form of velocity against that forward vane, which incloses the advanced bucket b^4 , in which the pressure is considerably less. In this way, a secondary propulsion is produced just prior to the communication of the buckets with the exhaust opening.

Inlet valve and operating mechanism.—The supply chamber a^{18} is provided internally and immediately beneath its inlet opening a^{14} , with an inlet valve E, adapted to normally rest against its seat e' . Connected to the valve E is a valve stem e^2 extending through a suitable stuffing-box, and continuing upward through the bearing a^{20} . The stem is provided with the fixed collars e^3 and e^4 , and with an intermediary loose collar e^5 normally maintained in a position immediately above the fixed collar e^3 . A helical compression spring e^6 is wound about the stem e^2 , and is positioned between the fixed collar e^4 and the loose collar e^5 . The tendency of this spring is to draw the stem upwardly, and accordingly to hold the valve against its seat. A second helical compression spring e^7 surrounds the spring e^6 , and also the fixed collar e^4 , and is positioned between the bracket a^{26} and the loose collar e^5 . The spring e^7 tends to force the loose collar e^5 and hence the fixed collar e^3 and stem e^2 downwardly to open the valve. The loose collar e^5 is provided with any approved form of forwardly extending lifter arm e^8 . It will now be manifest that the discharge valve operating mechanism is identical with the inlet valve operating mechanism, and furthermore both valves occupy a similar position relative to the crank-shaft D, though on opposite sides of the bracket a^{26} .

collar e^5 is provided with any approved form of forwardly extending lifter arm e^8 .

Discharge valve and operating mechanism.—Positioned below the explosion chamber, and as most clearly seen in Fig. 3, so as to lie tangentially with respect to the periphery of the rotor, is an abutting plate F. The lower edge of the plate F provides a downwardly divergent nozzle formation for the expanding gases of combustion, seen in Fig. 3. This plate has its under side suitably cut away in the form of an arc, seen in Fig. 6, to permit of its intersection by the periphery of the rotor, and in fact to present a precise mechanical fit therewith. The upper surface of the plate F is formed centrally with a depression f' , and near the upper end carries a pin f^2 . A valve f^3 is loosely mounted upon the pin f^2 , as a pivot, and in its uppermost position is adapted to tightly engage its seat f^4 to separate the explosion and expansion chambers. The under surface of the valve is provided centrally with a projection f^5 corresponding with the depression f' in the upper surface of the abutting plate, for the obvious purpose of centering the valve more securely in its lowermost open position, as will likewise be best understood from an inspection of Fig. 3. The upper surface of the valve is provided centrally with a perforated yoke f^6 . Connected with the valve f^3 through the medium of a link f^7 is a stem f^8 , extending through a suitable stuffing-box and continuing upward through the bearing a^{30} . The stem is provided with the fixed collars f^9 and f^{10} , and with an intermediary loose collar f^{11} normally maintained in a position immediately above the fixed collar f^9 . A helical compression spring f^{12} is wound about the stem f^8 , and is positioned between the fixed collar f^{10} and the loose collar f^{11} . The tendency of this spring is to draw the stem upwardly, and accordingly to hold the valve against the seat. A second helical compression spring f^{13} surrounds the spring f^2 , and also the fixed collar f^{10} , and is positioned between the bracket a^{26} and the loose collar f^{11} . The spring f^{13} tends to force the loose collar f^{11} and hence the fixed collar f^9 and stem f^8 downwardly to open the valve. The loose collar f^{11} is provided with any approved form of forwardly extending lifter arm f^{14} . It will now be manifest that the discharge valve operating mechanism is identical with the inlet valve operating mechanism, and furthermore both valves occupy a similar position relative to the crank-shaft D, though on opposite sides of the bracket a^{26} .

Change speed mechanism.—Change speed mechanism is provided for the purpose of transmitting the rotation of the primary shaft B to the crank shaft D, and through the medium of the splined shaft C. This

mechanism may comprise any of the well known essentials, and in this instance a plurality of six gears: G , G' , G^2 , G^3 , G^4 , G^5 , mounted upon the shaft B . The gear G is 5 shown to be the largest, and the gear G^5 the smallest. Suspended upon a loose collar c' from the splined shaft C in a well known manner, is an intermediary gear c^2 , which is constantly in mesh with a gear c^3 10 mounted directly above and fixedly to the splined shaft C . By raising or lowering the intermediary gear c^2 : through the manipulation of a lever c^4 , best seen in Fig. 4, which is adapted to be supported in any one 15 of the notches in the plate a^{21} corresponding with the one of the gears G , G' , G^2 , G^3 , G^4 , G^5 , on the primary shaft B : these latter may be successively brought into mesh therewith, and a rotation of gear c^3 and 20 hence the shaft C , occasioned. A second intermediary gear c^5 is fixedly mounted upon the splined shaft C , and is adapted to mesh with a gear d' mounted immediately above and upon the crank shaft D . In this manner, 25 the rotation of the primary shaft B may be finally transmitted with differing speeds, to the crank-shaft D .

Governor.—Mounted upon the crank-shaft D and positioned between the bearing 30 a^{25} and the gear d' , is any approved type of governor H , comprising the reciprocating sleeve h' . Fixed to the sleeve h' is an angular lever h^2 provided at its free extremity with a ball construction h^3 , adapted 35 to connect with spark-advancing mechanism, not shown. In this manner, as will be evident, the speed of the turbine may be automatically controlled through the medium of the governor.

40 *Pump.*—A double-acting pump J is mounted in the rear of the machine, and may be supported in an inclined position upon the base of the frame, as best seen in Fig. 1. This pump comprises a main cylinder j' and the inlet duct j^2 and outlet duct j^3 . The inlet duct is provided with an opening j^4 , and surrounding this opening is a carbureter flange j^5 adapted for direct connection with the carbureter. The outlet duct j^3 communicates directly with the opening e' to the supply chamber. The interior pump mechanism proper may be of any desired construction, and comprises an interior piston, not shown, and an exterior connecting arm j^6 suitably connected with the crank shaft D , as clearly seen in Fig. 2. In this manner, the reduced rotation of the crank-shaft D is directly utilized to impart a reciprocating action to the pump, as will be 50 readily understood.

Operating mechanism.—The crank-shaft D is provided intermediately of its bearings a^{21} and a^{22} with a pair of quick action cams, d^2 , d^3 , located immediately beneath 55 the lifter arms e^8 , f^4 . As will be most

clearly apparent from Fig. 3, these cams, during their rotation in the direction of the arrows, are adapted to lift the arms e^8 and f^4 against the action of the springs e^7 and f^{12} respectively. The two valves operate in 60 an identical manner, and by having a free fall open very suddenly. Furthermore, even should the explosion above the discharge valve f^3 be premature, the inner closing spring f^{12} will offer no serious, if any, mechanically appreciable resistance. In fact, 65 this spring, as well as the closing spring e^6 , will serve the function of recuperators by taking up wear on the part of the cams and lifter arms, or any expansions due to heat. 70 They also serve as intermittent buffer springs, and are consequently adapted to lengthen the life of the valve-operating mechanisms. Attention is directed to the 75 fact that the cams in my valve-operating mechanisms, are adapted to assist in suddenly opening rather than suddenly closing the valves. The two cams, if arranged to shift laterally, could, moreover, be readily 80 made to operate respectively, separate inlet and discharge valves mounted relative to 85 separate supply and explosion chambers in turn operatively positioned so as to cause 90 a reverse propulsion of the rotor.

Operation.—The operation is as follows:—In starting, the working fluid is 95 whirled around with the rotor until a cumulative charge within the explosion chamber is ignited and thus converted into gas having potential pressure. Coincidently the 100 harmonious operation of the parts, because suitably timed, is initiated. The continued operation of all the parts is thereafter dependent upon a pumping into the supply chamber of the proper mixture and regular 105 ignition. The discharge valve should preferably begin to open at the moment of ignition. The explosive power of the gaseous elements is thus converted into velocity 110 energy causing the gases to be directed past the free edge of the valve f^3 , through the nozzle formation imparted thereby, to the expansion chamber a^{14} . Thereafter the 115 gases travel directly into the buckets of the rotor, and more specifically still, directly against the lower, more advanced vane of any particular bucket. The given amount of air below the discharge valve is utilized as a cushion, by having the explosive gases, 120 in their endeavor to expand past the valve and acquire motion, impinge thereon and during this instant of expansion acquire velocity. The gases of combustion are accordingly given a definitely prescribed 125 initial direction, through the nozzle formation of the expansion chamber, and only again put under pressure after the particular receiving bucket has passed out of communication therewith. In case a high speed 130 is desired, the mechanism may be adjusted

to open the valve mechanically ahead of the explosion, while on the other hand, if a low speed is desired, the explosion itself may be compelled to overcome the resistance of the 5 inner spring f^{12} . The action of both valve mechanisms in the meantime is furthermore positive, and hence permits that degree of accurate adjustment which is required in engines of this character. Also the position 10 of the abutting plate F with relation to the periphery of the rotor, and because of its close mechanical fit therewith, is such that the velocity is necessarily projected only downwardly toward the auxiliary chamber 15 a^{15} . This chamber is intended to insure a secondary utilization of energy similar to the system employed in engines of the well-known compound type. If found feasible, this effect may be utilized against buckets 20 of a second rotor. In case the rotation on the part of the rotor and hence the movement of its peripheral buckets exceeds a certain limit, implying an incomplete explosion or combustion of the gases, this residual 25 velocity is permitted to rush around the bypass duct in the auxiliary chamber a^{15} , to expend itself upon a further advanced bucket once or twice removed, by way of exemplification in this instance, with but a 30 single intervening closed bucket b^5 . Moreover, in case a partial vacuum should be set up in the buckets, as they approach the exhaust opening, occasioning a resulting tendency of air to rush back and offer a detrimental 35 resistance to that bucket in momentary communication with the exhaust opening a^6 , this auxiliary pressure to the secondary explosive velocity will effectually offset such tendency. In this way, the maximum 40 energy in the form of velocity is utilized, and accordingly the desired efficiency of the turbine as a whole, attained.

Having fully described my invention, what I claim and desire to secure by Letters 45 Patent is:—

1. In an elastic fluid turbine, the combination of a casing having an outlet, a turbine rotor provided with buckets and having a close mechanical fit within said casing, said 50 outlet adapted to communicate with said buckets, an expansion chamber in successive communication with said buckets, agents whereby the thermal energy of the working fluid is supplied as kinetic energy to said 55 chamber, and a second chamber having a pair of openings spaced a distance corresponding with the distance between alternate of said buckets, said buckets in turn being adapted to communicate simultaneously with said chamber and one such opening, then simultaneously with the other of said openings and said outlet.
2. In an elastic fluid turbine, the combination of a casing having an exhaust outlet, a 60 turbine rotor provided with buckets and

having a close mechanical fit within said casing, said outlet adapted to communicate individually with said buckets, an expansion chamber communicating successively with said buckets, agents whereby the thermal 70 energy of the working fluid is supplied as kinetic energy to said chamber, and a second chamber having a single pair of openings in communication respectively with said exhaust outlet and expansion chamber, 75 the advanced opening of said second chamber with reference to the direction of movement of the rotor being arranged to communicate with a particular bucket in advance of the communication of such bucket 80 with said exhaust outlet and in advance of the communication with the latter of that following bucket which first received the motive fluid discharge coincident with its entry into said second chamber. 85

3. In an elastic fluid turbine, the combination of a suitable casing, a rotor having buckets and mounted for movement therein, an explosion chamber adapted to communicate with said buckets and provided with a carbureted fuel inlet, an igniter, a fixed 90 guide plate between said chamber and buckets and offering a close mechanical arcuate fit with the latter, a valve across said chamber, and mechanism for opening said valve in a direction toward said guide plate, whereby the expansion of the gases is converted into velocity of prescribed direction with relation to said buckets. 95

4. In an elastic fluid turbine, the combination of a suitable casing, a rotor having buckets and mounted for movement therein, an expansion chamber in communication with said buckets, means for supporting a motor fluid to said chamber, an abutting member projecting into said chamber and tangentially to said rotor, a valve for said chamber, said valve and member being respectively provided with a registering projection and depression, and mechanism for operating said valve. 100

5. In an elastic fluid turbine, the combination of a suitable casing, a rotor having buckets and mounted for movement therein, an expansion chamber in communication with said buckets, means for supplying a motive fluid to said chamber, an abutting member projecting into said chamber and conforming to said rotor, a valve pivotally mounted upon said member, a valve stem connected with said valve, means comprising a compression spring associated with said stem for maintaining said valve in its closed position, and mechanism for opening said valve. 110 115 120

6. In an elastic fluid turbine, the combination of a suitable casing, a rotor having buckets and mounted for movement therein, an explosion chamber, an expansion chamber communicating with said buckets, means 125 130

- for providing a carbureted fuel to said explosion chamber, an igniter, an abutting member projecting into said expansion chamber and conforming to said rotor, a 5 valve pivotally mounted upon said member, a valve stem connected with said valve, means comprising a spring surrounding said stem for closing said valve, means comprising another spring surrounding said stem 10 for opening said valve, and mechanism comprising a cam for controlling the action of said last-mentioned spring.
7. In an elastic fluid turbine, the combination of a suitable casing, a rotor having 15 buckets and mounted for movement therein, an expansion chamber communicating with said buckets and formed interiorly with a valve seat, an abutting member projecting into said chamber at an angle to said valve 20 seat, a valve pivotally mounted between said member and said seat, mechanism for positively moving said valve with respect to said seat and an explosion chamber adapted to communicate through said valve with said 25 expansion chamber.
8. In an elastic fluid turbine, the combination of a suitable casing, a rotor having buckets and mounted for movement therein, an expansion chamber adapted to communicate 30 with said buckets, an explosion chamber, means for supplying a carbureted mixture thereto, an igniter, a valve extending entirely across said chambers, and mechanism including a valve stem extending into 35 said explosion chamber for synchronously operating such valve and igniter.
9. In an elastic fluid turbine, the combination of a suitable casing having an exhaust opening, a rotor mounted for movement 40 therein and provided with buckets adapted to communicating with said opening, an explosion chamber adapted to have communication with said buckets, a supply chamber, an inlet valve flexibly mounted between said 45 chambers, a stem connected therewith, means comprising a spring surrounding said stem for closing said inlet valve, means comprising another spring surrounding said stem for opening said inlet valve, a discharge valve movably attached at one side between 50 said chamber for closing said explosion chamber, a stem flexibly connected therewith, means comprising a spring surrounding said stem for closing said discharge valve, means comprising another spring 55 surrounding said stem for opening said discharge valve, a shaft, change speed mechanism operatively connecting said shaft and rotor, and means including cams on said shaft for respectively controlling the action 60 of said valve-opening springs, the arrangement being such that the operation of said valves is synchronous.
10. In an elastic fluid turbine, the combination of a suitable casing having an exhaust opening, a rotor mounted for movement therein and provided with peripheral buckets communicating with said exhaust opening, a water-jacketed explosion chamber adapted to have communication with 70 said buckets, a supply chamber communicating with said explosion chamber and provided with an inlet for the carbureted air, a pivoted discharge valve for closing said explosion chamber and adapted to swing 75 toward said buckets, a stem movably connected with said valve, a shaft, change-speed mechanism operatively connecting said shaft and rotor, means comprising a cam on said shaft for effecting the movement of 80 said stem, a governor upon said shaft, a spark-advancing lever connected with said governor and distinct means interposed between said valve and rotor whereby to direct the gases relative to said rotor as initiated 85 by said discharge valve.

Signed by me, this 31st day of May, 1913.

MAX C. WEBER.
